FIG. 1 is a top, front, right perspective view of a bag showing my new design;
FIG. 2 is a front view thereof;
FIG. 3 is a right side view thereof;
FIG. 4 is a left side view thereof;
FIG. 5 is a top view thereof;
FIG. 6 is a bottom view thereof; and,
FIG. 7 is a top, front, right perspective view of an alternative claimed configuration of a bag showing our new design. The uneven-length broken lines immediately adjacent to the shaded area define the bounds of the claimed design and form no part thereof. The even-length broken lines showing the remainder of the bag represent unclaimed subject matter and form no part of the claimed design.
